UNITED STATES PATENT OFFICE.

HARRY J. NICHOLS, OF WASHINGTON, DISTRICT OF COLUMBIA.

MARKER-SHELL.

1,394,335.

Specification of Letters Patent.

Patented Oct. 18, 1921.

Application filed December 15, 1919. Serial No. 345,163.

To all whom it may concern:

Be it known that I, HARRY J. NICHOLS, a citizen of the United States, residing at Washington, District of Columbia, have invented new and useful Improvements in 5 Marker-Shells, of which the following is a specification.

This invention relates to improvements in projectiles and more particularly to that 10 type now known as marker shells. These shells after being fired and upon striking the surface of a body of water or shortly thereafter discharge intact a body of chemicals adapted to produce a signal such as a 15 light or a body of smoke, according to the type of chemical used. For example, a light would be desirable at night while a smoke cloud would be preferable in daylight. By varying the chemical compound both light 20 and smoke may be obtained.

This type of projectile is of particular value in military and naval operations in marking or identifying a spot where a projectile falls thus serving as a guide or point 25 of origin while maneuvering.

The shell is of particular value in connection with the usual fire control to mark the point where the projectile strikes, or for intelligence purposes, or to illuminate or obscure 30 by smoke the area circumjacent to the spot where the projectile strikes thereby revealing or obscuring, as desired, the vessels or other bodies within such area.

It is, of course, obvious to those skilled in 35 the art that various other objects and advantages may be obtained by a projectile of this character in its use against hostile vessels, batteries, aircraft or other military forces.

Projectiles of this general character heretofore suggested have employed certain chemicals associated with an explosive whereby when the projectile strikes the water the entire container explodes through the agency 45 of a fuse, detonator or the like thereby liberating the chemicals after the shell has penetrated the water in which case the chemicals either sink without functioning or if they do function such takes place in small isolated 50 quantities making a signal invisible at any material distance and of relatively short duration.

It is, therefore, one of the objects of the present invention to overcome the objections 55 above recited and to provide a simple and practical construction which will enable the

objects of the marker shell to be realized in a reliable manner when suitably employed.

Broadly speaking, the invention provides means of ejecting a chemical or assembly 60 intact, which assembly will be hereinafter referred to as the marker, whereby the production of the signal, illumination, or smoke will be highly effective in use and operation.

Other objects will be in part obvious and 65 in part hereinafter pointed out in connection with the accompanying drawings which show one of the various possible modifications of the invention and wherein like reference characters denote corresponding 70 parts. In these drawings,—

Figure 1 is a longitudinal view of a projectile embodying the improvements and principles of the invention.

Fig. 2 is a detail view of the front part of 75 the shell showing the device employed to prevent rebound or ricocheting of the projectile when striking the water.

Fig. 3 is a detail view of the front end 80 of the marker, and

Fig. 4 is a longitudinal sectional view of a modified form of my invention.

Referring now to the drawings in detail and more particularly Figs. 1, 2 and 3, 1 designates the body portion of my improved 85 shell or projectile, said body being hollow as shown; and being provided with a base plug 2, detachably secured thereto in any desired way, as, for example, by two or more shear pins 3, as shown.

The front end of the shell body 1 is closed by the igniter 4, secured thereto in any desired way, as, for example, by the screw thread connection shown.

One of the main features of my invention 95 resides in the means and constructions that are provided to prevent the shell from rebounding or ricocheting when first striking water, without at the same time increasing the air resistance of the projectile. For the 100 successful employment of signal projectiles of the character described, it is necessary for the projectile to operate at the point where it first strikes the water, and if the projectile ricochets the signal may be ejected 105 in the air at some distance from the point where the projectile first struck. It is also important that the air resistance be not increased in order that the projectile may be 110 constructed to follow the trajectories of the usual types of projectiles with ogival points, since projectiles of the character described

herein are often employed in conjunction with the usual types of shell. The usual forms of blunt nose non-ricocheting projectiles have greater air resistance than projectiles of the usual form and, therefore, follow a different trajectory and are for this reason less desirable but may be used under certain circumstances.

The means above referred to comprise the application to the front or upper part of the shell body 1 of a truncated cone, or truncated ogive, as shown. The truncated portion of the shell body is recessed to receive the fuse igniter 4, previously described. The igniter 4 is constructed to form with the shell a flat surface without projections and perpendicular to the axis of the projectile. To the flat surface so formed a disk 5 is secured by one or more screws 6 (2 being shown in present embodiment of my invention). To the disk 5, which is threaded on the periphery, is screwed a light cap or false point 7, which in the present embodiment is shown ogival in shape, though other conoidal shapes might be employed if desired.

The interior of the shell body 1, which is cylindrical in shape, contains the marker composed of a float 8, which I prefer to be of wood, with a base plate 9 and attached to the float in any way desired, as for example, by screws, of which two are shown in the drawing, said base plate closes the cylindrical cavity in the float 8 and acts as ballast to hold the float 8 in an upright position when floating. The cylindrical cavity in the float 8 is filled with a pyrotechnic mixture 10, substantially as shown.

Another feature of my invention resides in the means provided for igniting the pyrotechnic mixture after the marker has been ejected and after it rises to the surface. It is to be understood, however, that the invention is not to be limited in this respect, since because of the various uses of the projectile described various chemical mixtures may be employed, some of which may be ignited directly by the igniter and others by the action of air after reaching the surface.

The means just referred to comprise the cap 11 attached to the float 8 by metal nails or other suitable means, and having a circular opening at the center and a recess into which the obturator 12 is pressed. The periphery of the obturator 12 is formed to fit closely the indentation in the cap when seated therein, and forms a gas tight joint therewith. The obturator 12 further encases and holds the time fuse 13. The cap 11 which fits tightly over the top of the float 8 prevents the gases under pressure of the ejection charge 14 from entering the interior of the marker or the pores in the float 8, which would cause the float 8 to bind in the shell and to be damaged when ejected.

Above the marker is the ejection charge

14, which I prefer to have in the form of a ring of compressed black powder. Surrounding the ejection charge 14, and between the cap 11 and the shell body 1 is a cushion 15 of felt or the like, to lessen the shock on the marker when the shell strikes. Likewise, a cushion 16 is placed between the base plate 9 and the base plug 2 to lessen the shock on the marker when the projectile is fired and when the marker is ejected.

From the foregoing description in connection with the accompanying drawings, the operation of my improved projectile is as follows:—

On striking the water the false cap 7 and the attached disk 5 are detached from the projectile when the screws 6 are severed by the force of the impact of the projectile and the water. The screws 6 are preferably constructed with a breaking groove 17 at the juncture of the shell body 1 and the disk 5, as shown in Fig. 2. In any case, the screws 6 should be of such size and material that they would break instead of the screw connection 18. The breaking away of the cap 7 and the attaching disk 5 after severing of the screws 6 leaves a flat surface at the end of the shell, this flat surface having preferably 50 to 60 per cent. of the area of the shell at its largest transverse section, which occurs at the part technically known as the bourrelet. The projectile when so constructed will not be deflected by the water, nor will it ricochet, but will penetrate the water.

As the shell enters the water the igniter 4 operates to ignite the ejection charge 14, the igniter being constructed to function in this way, as is commonly practised and well understood. The gases generated by the ejection charge 14 after being ignited exert great pressure on the cap 11 of the marker, this pressure being transmitted by the marker to the base plug 2 tending to force it to the rear. At the same time the time fuse 13 is ignited by the igniter 4 and the ejection charge 14 and begins to burn. The shear pins 3 not being strong enough to restrain the force exerted by the powder gases are severed and the base plate 2, cushion 16, and marker are ejected from the shell body. As soon as the marker is free of the shell it ascends to the surface of the water by reason of the buoyancy imparted to it by the float 8. Shortly after arriving at the surface the pyrotechnic mixture 10 is ignited by the time fuse 13, whose length of burning is chosen to produce this result. The pyrotechnic mixture on being ignited produces sufficient pressure within the float 8 to force the obturator disk 12 carrying the time fuse 13, out of its recess in the cap 11, producing a vent through which the flame and smoke of the pyrotechnic mixture emerge.

- When a pyrotechnic mixture is employed which burns so actively when ignited that it is not extinguished by submergence under water, the ejection charge 14, the obturator 5 12, and the time fuse 13, described above, may be dispensed with, in which case the gases generated by the burning pyrotechnic mixture may be utilized for ejecting the marker.
- 10 It will thus be seen that I have invented and provided means for ejecting the pyrotechnic charge from the projectile and of protecting it from the damaging or extinguishing effect of the surrounding water into 15 which it is projected with great violence; bringing it intact to the surface, where it is ignited under advantageous conditions and have given the products of combustion egress to the surrounding atmosphere, where 20 they may produce a visible signal or other effects, thereby accomplishing the objects sought in an efficient and reliable manner.
- In the modified form of my invention, as shown in Fig. 4, 30 designates a hollow shell body which is provided with a base plug 31 25 detachably secured to the shell body 30 by shear pins 32. The shell body is formed with one or more ducts or channels 33, disposed longitudinally, or inclined to the longitudinal, communicating with a pressure 30 chamber 34, within the shell body 30. The interior of the shell contains a circular piston 35, and a marker 36. The marker 36 is composed of suitable chemicals for producing smoke or flame, or both, said chemicals being in the solid, liquid or gaseous state as may be preferred, for producing the military or naval objects of the shell, it being essential that the material or combination 35 of materials and parts be light enough in weight to float on the water after the marker has been discharged from the shell. It is also preferable that the marker have the quality of being ignited through chemical 40 action to produce flame or smoke or both.
- It will be evident that when the projectile strikes the water, the water enters the chamber 34, above the piston 35, through the channel or channels 33 provided for this 45 purpose. This water is under great pressure due to the relative velocity of the shell and the body of water into which it is plunged and exerts a strong force toward the rear or base of the projectile. This force 50 being transmitted from the piston 35 to the base plug 31 by the material of the marker 36 severs the shear pins 32 and forces out the base plug 31 after which the marker 36 is ejected. The marker 36 thus being ejected 55 from the base of the shell and being lighter than water, rises to the surface where it ignites and burns producing a brilliant flame or a large quantity of smoke, whereby the objects of the invention are accomplished.
- 5 Metallic sodium is the preferable chemi-
- cal employed in the marker but it is to be understood that the invention is not limited in this regard since other chemicals, both solid, liquid or gaseous are suitable for obtaining the objects of the present invention. 70
- While the accompanying drawings illustrate what I believe to be the preferred embodiments of my invention, it is to be understood that the invention is not limited thereto, but that various changes may be made 75 in the construction, arrangements and proportions of the parts without departing from the scope of the invention as defined in the appended claims.
- 80 What I claim is:—
1. In a projectile of the character described, in combination, a shell, a detachable base, a floating chemical marker, and means for ejecting this marker rearwardly from the shell on striking the water comprising an igniter and an ejection charge whereby the gases generated by the explosive after being ignited will constitute a means for ejecting the marker from the shell. 85
  2. In a projectile of the character described, in combination, a shell, a detachable base, a chemical marker to float on the water, means for ejecting this marker rearwardly from the shell, comprising an igniter and an ejection charge, and means for protecting the marker from the effects of the explosive. 95
  3. In a projectile of the character described, in combination, a shell, a detachable base, a chemical marker to float on the water, means for ejecting this marker rearwardly from the shell, comprising an igniter and an ejection charge, and means for protecting the marker from the effects of the explosive on ignition of the ejection charge including a metal cap carried by the marker adjacent the ejection charge. 100
  4. In a projectile of the character described, in combination, a shell, a detachable base, a floating chemical marker, an ejection charge in the form of a ring between the front of the projectile and the marker, and means for protecting the marker from the effects of the ejection charge and securing its ignition including a protecting cap carried by the marker adjacent the ejection charge and a time fuse of short duration, carried by said cap and associated with the marker and said ejection charge. 110
  5. In a projectile of the character described, in combination, a shell, a detachable base, a floating chemical marker, an ejection charge in the form of a ring between the front of the projectile and the marker, and means for protecting the marker from the effects of the ejection charge and securing its ignition including a protecting cap carried by the marker adjacent the ejection charge, a time fuse of short duration associated with the marker and said ejection charge. 120
  6. In a projectile of the character described, in combination, a shell, a detachable base, a floating chemical marker, an ejection charge in the form of a ring between the front of the projectile and the marker, and means for protecting the marker from the effects of the ejection charge and securing its ignition including a protecting cap carried by the marker adjacent the ejection charge, a time fuse of short duration associated with the marker and said ejection charge. 125
  7. In a projectile of the character described, in combination, a shell, a detachable base, a floating chemical marker, an ejection charge in the form of a ring between the front of the projectile and the marker, and means for protecting the marker from the effects of the ejection charge and securing its ignition including a protecting cap carried by the marker adjacent the ejection charge, a time fuse of short duration associated with the marker and said ejection charge. 130

charge, and an obturator seated in said protecting cap and incasing said time fuse.

6. In a projectile of the character described, in combination, a shell, a detachable base, a chemical marker within said shell, means for ejecting said marker rearwardly from the shell, and means for insuring operation of the marker at the point where the projectile first strikes the water.

10 7. In a projectile of the character described, in combination, a shell, a detachable base, a chemical marker within said shell, means for ejecting said marker rearwardly from the shell, and means for insuring operation of the marker at the point where the projectile first strikes the water comprising a detachable ogival at the forward end of the shell, said detachable ogival comprising in part a cap fitting over a truncated conoidal 20 shape terminating in a flat surface free from projections and including an area of 50 to 60 per cent. of the area of the transverse section of the shell.

8. In a projectile of the character described, in combination, a shell, a detachable base, a marker, means for ejecting this

marker rearwardly from the shell intact, and means for insuring operation of the marker at the point where the projectile first strikes the water and lessening the air resistance of 30 the shell including a light metal cap detachably secured to the shell.

9. A marker projectile including a shell body, a marker to float on the water and means for ejecting the marker rearwardly 35 from said body when the projectile strikes the water.

10. A marker projectile including a shell body, a detachable base, a marker to float on the water, and means for ejecting said 40 marker rearwardly from said body with said detachable base when the projectile strikes the water.

11. A marker projectile including a shell body, a detachable base, an assembly to float 45 on the water, and means for detaching the base and ejecting said assembly intact from said body when the projectile strikes the water.

Signed at Washington, District of Colum- 50 bia, this first day of October, 1919.

HARRY J. NICHOLS.
